CLAIM

The ornamental design for umbrella base, as shown and described.

DESCRIPTION

FIG. 1 is a perspective view of the front and top of the umbrella base according to one embodiment of my new design;

FIG. 2 is a top view thereof;

FIG. 3 is a left side view thereof, the right side view being a mirror image thereof;

FIG. 4 is a bottom side view thereof; and,

FIG. 5 is a perspective view of the front and bottom thereof. The broken lines shown represent portions of the umbrella base that form no part of the claimed design.
